DESIGN FOR A WAFFLE BAKER

Jean O. Reinecke and James F. Barnes, Chicago,
Ill., assignors to McGraw Electric Company,
Elgin, Ill., a corporation of Delaware

Application August 10, 1939, Serial No. 86,589

Term of patent 7 years

To all whom it may concern:

Be it known that we, Jean O. Reinecke and James F. Barnes, citizens of the United States, both residing at Chicago, in the county of Cook and State of Illinois, have invented a new, original, and ornamental Design for a Waffle Baker, of which the following is a specification, reference being had to the accompanying drawings, forming part thereof, in which

Fig. 1 is a top plan view of a waffle baker showing our new design,

Fig. 2 is a side elevational view thereof,
Fig. 3 is a front elevational view thereof, and
Fig. 4 is an enlarged fragmentary sectional view of the casing portion of the waffle baker, taken on the line 4—4 of Fig. 1.

We claim:

The ornamental design for a waffle baker, substantially as shown.

JEAN O. REINECKE.
JAMES F. BARNES.
